UNITED STATES PATENT OFFICE.

PETER KAWINSKI, OF BUFFALO, NEW YORK.

DESIGN FOR A RAT-TRAP.

53,851.

Specification for Design.

Patented Sept. 16, 1919.

Application filed October 1, 1918. Serial No. 256,470. Term of patent 7 years.

To all whom it may concern:

Be it known that I, PETER KAWINSKI, a citizen of Ukraine, having declared my intention to become a citizen of the United States, residing at Buffalo, and State of New York, have invented a new, original, and ornamental Design for a Rat-Trap, of which the following is a specification, reference

being had to the accompanying drawing, forming part thereof.

The figure is a perspective view of a rat trap, showing my new design.

I claim:—

The ornamental design for a rat trap, as shown.

PETER KAWINSKI.
